UNITED STATES PATENT OFFICE.

ALFRED WOOLEN, OF OKMULGEE, OKLAHOMA, ASSIGNOR OF ONE-HALF TO L. M. TRYER, OF OKMULGEE, OKLAHOMA.

PISTON-RING SQUEEZER.

Application filed September 19, 1922. Serial No. 589,277.

To all whom it may concern:

Be it known that I, ALFRED WOOLEN, a citizen of the United States, residing at Okmulgee, in the county of Okmulgee and 5 State of Oklahoma, have invented certain new and useful Improvements in Piston-Ring Squeezers, of which the following is a specification.

My invention relates to a tool for use in 10 applying piston rings to the pistons of an internal combustion engine and is of the type that is known as a "ring squeezer" meaning thereby that the rings are placed in position by squeezing them so that they 15 may fit into the cylinder.

One of the objects of the invention is to provide a device of this character which will enable the operator to use both hands in inserting the piston in the cylinder.

20 A further object is to provide a device with removable handles so that the operator can take same down to replace any broken parts or for replacement in tool box.

Another object is to provide a construction 25 so that the handles can be set at various angles to facilitate inserting the piston in the cylinder.

With these general objects in view, my 30 invention consists in certain novel and peculiar features of construction and combination of parts as hereinafter described and claimed, and in order that it may be fully understood, reference is to be had to the accompanying drawing, in which:

35 Fig. 1 is a perspective view of the ring squeezer, showing handles;

Fig. 2 is a sectional elevation showing the method of using when inserting the piston from the bottom of the cylinder;

40 Fig. 3 is a plan view showing the range of adjustment of the band for varying sizes of pistons;

Fig. 4 is a section on the line 4-4 of Fig. 3;

45 Fig. 5 is a section on the line 5-5 of Fig. 3;

Fig. 6 is a section on the line 6-6 of Fig. 5.

In the drawings, 1 is an outside band and 50 2 is an inside band, both being formed of thin springy sheet metal each provided at its inner end with offset ears 4 and 5 respectively, reinforced by metal strips 6 and 7 and pivotally connected to the ends 8 and 9 55 of crossed handles 10 and 12 pivoted to-

gether at 13 and to the said offset ends and ears.

For holding the handles in adjusted position relative to the said hands, I provide set screws 14 and 15 secured to said bands 60 and having thumb nuts 16 and 17 for clamping together the handles and band. Pivoted to one of the handles 12 is a ratchet bar 18 engaging the other handle for holding the said handles in adjusted position, a tension 65 spring 19 holding the said ratchet in engaged position.

The band is capable of being adjusted to fit varying sizes of pistons and may have indicia marked therein, as at 20, to indicate the size of the piston to which the said band is adjusted.

The inner band 2 has a screw 21 riveted or otherwise suitably secured thereto and engaging the slot 22 in the outer band. A 75 thumb nut 23 engages the said screw and when set up holds the two bands in adjusted position. The inner band 2 is also provided with a slot 24, the elongated rectangular tongue 25 of the screw 27 slidably engaging 80 therewith and the said tongue on the inner side of the said band 2 having secured thereto a sheet of metal 26 to prevent the said slot from catching on a ring. The screw 27 passes through a closely fitting aperture 28 85 in the band 1 and is provided with a thumb nut 29, for securing the two bands in adjusted relation.

The inner end of each band is tapered as at 30 and 31 so as not to interfere in any 90 way with the placing of the ring in position.

All the screws are made with square shoulders and riveted to the bands so that there will be no danger in turning in making the necessary adjustments.

Operation.

When it is desired to place a ring in position, the band is first set to a size corresponding with the size of the piston. The 100 piston ring is then squeezed up tight around the piston and held in this position by the ratchet locking the tool in set position. The piston may then be inserted in the cylinder with both hands of the operator, the handles 105 being adjusted to the suitable angle to facilitate operation.

On both ends of some cylinders and on the lower end of all of them, a chamfer or concave 32 is provided in which the thin 110

band of metal is adapted to fit as shown in Fig. 2.

From the above description it will be apparent that I have produced a device of the character enumerated as desirable and while I have illustrated and described the preferred form of the invention, it will be understood that I reserve the right to all changes properly falling within the spirit 10 and scope of the appended claim.

Having described my invention, what I claim as new and desire to secure by Letters Patent is:

15 A ring squeezer comprising a two part circular band of thin springy sheet metal adapted to surround the piston and having

a free and unobstructed edge adapted to fit into the chamfer of the cylinder of an engine, means for adjusting the said parts of the band relative to each other to vary the 20 diameter of the band, each part being provided at one end with an offset ear located within the plane of the band, a pair of crossed handles pivoted together, means for locking the handles together to hold the band in set position, each handle pivoted to one of the said ears to permit angular adjustment of the said handles relative to the plane of the band.

In testimony whereof I affix my signature.

ALFRED WOOLEN.
